UNITED STATES PATENT OFFICE.

HANS KREUSLER, OF BERLIN-WILMERSDORF, HANS GERDIEN, OF BERLIN-SCHMAR-GENDORF, AND MARCELLO VON PIRANI, OF BERLIN-WILMERSDORF, GERMANY, ASSIGNORS TO SIEMENS & HALSKE A.-G., OF BERLIN, GERMANY, A CORPORATION OF GERMANY.

INCANDESCENT LAMP.

1,194,643.

Specification of Letters Patent. Patented Aug. 15, 1916.

Application filed September 22, 1914. Serial No. 863,030.

To all whom it may concern:

Be it known that we, HANS KREUSLER, a German citizen, and resident of Berlin-Wilmersdorf, Germany, HANS GERDIEN, a German citizen, and resident of Berlin-Schmar-gendorf, Germany, and MARCELLO VON PIRANI, an Italian citizen, and resident of Berlin-Wilmersdorf, have invented certain new and useful Improvements in Incandescent Lamps, of which the following is a specification.

Our invention relates to a novel incandescent lamp with carbon filament and consists essentially in providing a gas filling for the same such as has been used heretofore in connection with metal filament lamps. It is known that carbon filaments will easily disintegrate in the vacuum of incandescent lamps and gas fillings have been proposed 15 for preventing this disintegration. On the other hand also for diminishing the heat losses in the vacuum, arrangements have been proposed whereby the several parts of the filament are placed as near as possible 20 to each other.

Our invention in a certain aspect consists in a combined employment of these two modes and results in a novel and unexpected effect in so far that without danger of disintegration of the carbon filament the temperature thereof may be run very high and on the other hand by virtue of the close arrangement of the several parts of the filament the losses by heat conduction and convection in the gas are decreased to such an extent that the watt consumption of the lamp will be considerably reduced. A filament of this construction is preferably of helical form with closely adjacent turns, 35 although other forms may also be used, all these forms resulting in a "concentration" of the filament, so that the aforementioned effect will be attained. In the claims we have used the expression "filament of concentrated construction" for defining filaments of this kind.

It is known that arrangement of the aforementioned kind can also be made in lamps having metal filaments; a great disadvantage, however, is found in this case in that the metal filament at the temperatures to be considered are much softer than carbon filaments, so that care must be taken in arranging the several parts of the metal filament not too closely to each other for

obtaining the most favorable effect. If carbon filaments are employed in this regard much more will be accomplished. In particular the filaments will be so disposed that comparatively large helices are formed and 60 that the filament is fixed between two conductors. The employment of carbon filaments instead of metal filaments has in addition to this the advantage that much shorter filaments or essentially thicker and 65 stronger filaments may be used and that much more freedom is given in the arrangement of the filament as well as in choosing the voltages and the candle-powers than in case metal filaments are used. In case of 70 carbon filaments it will especially be possible to make lamps for small candle-powers and the usual voltages in spite of the comparatively high current load.

According to our invention we employ a 75 pressure for the gas filling in the lamp which is higher than the atmospheric pressure which will result in an especially favorable effect. Heretofore, in view of the danger of explosion no attempts have been 80 made to construct incandescent lamps having an interior overpressure, besides it has not been known that an immediate advantage can be attained by increasing the gas pressure. We have found that by increasing 85 the pressure an essentially higher load of the filament can be attained without fear that the disintegration of the carbon may take place. Although at the higher gas pressure the losses by heat convection will 90 become greater, it is possible to almost completely compensate these losses by the more favorable disposition of the filament which becomes possible with carbon filaments, so that by the aid of the higher pressure in 95 the lamp bulb and the simultaneous employment of relatively large filament helices with closely adjacent turns, lamps may be manufactured having a smaller watt consumption than those with metal filaments 100 of high melting point. The danger of bursting of the lamp bulb through the interior excess of pressure may be prevented by choosing stronger glass walls and a kind of glass which is more suited for this purpose, also if desired the bulbs may be provided with closely fitting wire nets. These wire nets may have relatively large meshes and may also be let into the interior of the glass.

One mode of carrying our invention into effect consists in using as a gas filling mercury vapor alone or in mixture with other indifferent gases such as nitrogen and argon. Especially in connection with carbon filaments the employment of mercury vapor, results in a particular advantage and this because the carbon filament does not enter into reaction as easily as with many other gases, especially if these are not entirely pure. This reaction will become especially important at very high temperatures to which according to our present invention the carbon filament of the lamp is exposed.

Besides the mercury vapor in the lamp bulb also nitrogen or argon or the like may be contained according to our present invention. The advantage of this consists especially therein that when switching the lamp into circuit from the start a certain gas pressure is present in the bulb even if no mercury has yet been evaporated.

In order to prevent the mercury after having condensed from coming into contact with the filament it is preferable to provide a condensing chamber at the side of the lamp bulb from which chamber the mercury after condensation will be carried back into the space below the filament where it will again evaporate under the influence of the heat of the filament. We have found that the ordinary arrangement of the incandescent body in a glass bulb has proved to be unsuited in many cases for the more and more increasing temperatures and vapor pressures, because the glass becomes soft at those places which are nearest to the incandescent body and will be deformed or eventually burst in consequence of the relatively large pressure in the interior of the bulb. In such cases the incandescent body is provided with an especial envelop which is either made of glass or if desired of a material through which light passes and which is of a high melting point. For this purpose quartz, hard glass or the like has proven to be especially well suited. By this envelop an especial chamber will be formed in which there is preferably contained liquid mercury. The incandescent body is mounted at such a distance from the surface of the mercury that the required quantity of vapor can be generated under normal load of the incandescent body. The interior chamber is completely filled with mercury vapor and soon after switching in the current a condition of equilibrium will arise, so that no more mercury will evaporate. This envelop at the upper end is connected with the remaining part of the bulb, so that in the interior of the bulb the same pressure will exist throughout. The bulb is preferably filled at the start with another indifferent gas, such as nitrogen or argon or the like under a cer-

tain pressure, whereby also the interior chamber will be filled with this gas. As soon as current flows through the incandescent filament and mercury vapor forms in the interior chamber, the originally consisting gas will be pushed entirely or partly from the interior chamber toward the exterior space of the bulb and the pressure on either side of said envelop will be increased. As the pressure on either side of said envelop is the same the latter may be heated up to a very high temperature without danger. The outer wall of the bulb in this arrangement will remain relatively cool and by reason of this will be able to safely withstand a comparatively high pressure. According to our invention this envelop may further be modified in such a manner that it consists of a tube which at its lower end is closed up by means of mercury and therefore separated from the remaining part of the bulb. In this lamp construction which is especially simple, the incandescent body is relatively close to the exterior wall of the bulb, which due to the presence of the mercury between the wall of the bulb and the incandescent body the exterior wall, however, can never assume a too high temperature, the same remaining always below the evaporating temperature of the mercury.

In the accompanying drawing we have shown three forms of lamps according to our present invention.

Figure 1 represents a lamp having the above described envelop around the electrodes and the filament, said envelop being closed at its lower end. Fig. 2 shows a construction differing from that of Fig. 1 in that said envelop is open at its lower end and closed up by the liquid mercury contained in the lamp bulb. Fig. 3 is a construction similar to that shown in Fig. 1 comprising some additional features for supporting said envelop within the bulb of the lamp and for protecting the filament.

The construction of the three types of lamp as shown is as follows:—In Fig. 1 *a* is the bulb comprising an upper cylindrical part and a lower spherical part. The conductors *e* are carried through said cylindrical part of the bulb downward to about the center of said spherical part. The carbon filament *d* is mounted upon the lower ends of said conductors. The envelop *b* which surrounds said conductors and said filament is essentially of cylindrical shape and is closed up at the lower end, so that the conductors and the filament will be entirely surrounded by the same. The mercury *c* is positioned at the bottom of said envelop, so that the evaporation and condensation of the mercury will take place essentially within the interior of the envelop. The envelop is mounted within the glass bulb in any convenient manner and in such

a way that at the upper end a passage will be provided between the interior of the envelop and the interior of the glass bulb.

Fig. 2 shows a construction which differs from that of Fig. 1 in that the envelop *v* is entirely of a cylindrical form with open ends and is carried down near the bottom of the glass bulb. The mercury is placed at the bottom of the bulb and will provide a closure at the under part of the envelop between the space of the envelop and that of the glass bulb. In this construction also the conductors *e* are prolonged downward for the purpose of having the filament *d* near the surface of the mercury.

The construction shown in Fig. 3 is in principle the same as that of Fig. 1 and comprises additional means for properly supporting the envelop *b* within the glass bulb. 20 *a*. These supporting means consist of two preferably resilient metal pieces *l* and *m* of which the former is interposed between the upper end of the envelop and the upper part of the glass bulb and the latter somewhat 25 lower between the envelop and the lower end of the cylindrical part of the glass bulb. A wire net *f* which consists of heat-resisting wire is mounted by means of insulating sleeves *i* upon the conductors and serves 30 among other purposes for rendering the motion of the gases and vapors more uniform.

Having thus described our invention we claim as new and desire to secure by Letters Patent of the United States:—

35 1. In an incandescent lamp the combination of the lamp bulb, a gaseous filling therein, conductors projecting into the interior of said bulb, a carbon filament with filament parts which are closely adjacent to each 40 other to reduce convection and conduction and carried between the ends of said conductors, an envelop of a material through which light passes, said envelop being mounted within said bulb and surrounding 45 at some distance said conductors and said filament, a passage between the interior of said envelop and the interior of said bulb near the upper end of said envelop, and liquid mercury placed at the bottom of said 50 envelop near to said filament.

2. In an incandescent lamp the combination of the lamp bulb, a gaseous filling therein, conductors projecting into the interior of said bulb, a carbon filament with 55 filament parts which are closely adjacent to each other to reduce conduction and convection and carried between the ends of said conductors, an envelop of a material through which light passes, said envelop surrounding 60 at some distance said conductors and said filament, fastening means between said envelop and said bulb, a passage between the interior of said envelop and the interior of

said bulb near to the upper end of said envelop, and liquid mercury placed at the bottom of said envelop near to said filament.

3. In an incandescent lamp the combination of the lamp bulb, a gaseous filling therein, conductors projecting into the interior of said bulb, a carbon filament with filament parts which are closely adjacent to each other to reduce conduction and convection and carried between the ends of said conductors, an envelop of a material through which light passes, said envelop surrounding 75 at some distance said conductors and said filament, fastening means between said envelop and said bulb, a passage between the interior of said envelop and the interior of said bulb near to the upper end of said envelop, liquid mercury placed at the bottom of said envelop near to said filament, and a protective wire net mounted above said filament.

4. An incandescent lamp comprising in 85 combination a lamp bulb, a gaseous filling therein and a carbon filament of concentrated construction therein.

5. An incandescent lamp comprising in combination a lamp bulb, a filling of an indifferent gas therein, and a carbon filament 90 of concentrated construction therein.

6. An incandescent lamp comprising in combination a lamp bulb, a filling of an indifferent gas of higher than atmospheric 95 pressure and a carbon filament of concentrated construction therein.

7. An incandescent lamp comprising in combination a lamp bulb, a gas filling therein containing mercury, and a carbon filament 100 of concentrated construction therein.

8. An incandescent lamp comprising in combination a lamp bulb, a gas filling therein containing a metal vapor, and a carbon filament of concentrated construction 105 therein.

9. An incandescent lamp comprising in combination a bulb, a gas filling therein containing a mixture of mercury vapor and an indifferent gas and a carbon filament of 110 concentrated construction therein.

10. An incandescent lamp comprising in combination a bulb, a gas filling therein containing a mixture of mercury vapor and nitrogen and a carbon filament of concentrated construction 115 therein.
